UNITED STATES PATENT OFFICE.

WALTER LOYD LINTON, OF INDEPENDENCE, KANSAS.

VENDING MACHINE.

Application filed December 8, 1924. Serial No. 754,599.

My invention relates to improvements in vending machines of the type in which the articles of merchandise to be sold, are stacked one upon another, in a vertical magazine, a movable coin-controlled ejector being provided at the lower end of the magazine for ejecting the lowermost of the articles, each time said ejector is operated.

One object of the invention is to provide a machine which may be used for vending single cigarettes or other similarly shaped articles, although its use is not restricted to this field.

A further object of the invention is to provide the ejector with a relatively narrow terminal upon which the lowermost article of the stack normally rests, so that when the ejector is operated to move the article and said narrow portion beyond the magazine, the article may tilt and fall from said narrow portion, to discharge through the outlet of the machine.

With the foregoing in view, the invention resides in the novel subject matter herein-after described and claimed, the description being supplemented by the accompanying drawings.

Figure 1 is a front elevation of a vending machine constructed in accordance with my invention.

Figure 2 is an enlarged vertical sectional view on line 2—2 of Fig. 1, showing the normal relation of parts.

Figure 3 is a view similar to a portion of Fig. 2, illustrating the manner in which the machine operates to eject the lowermost article from one of the magazines.

Figure 4 is a horizontal sectional view on line 4—4 of Fig. 2.

Figure 5 is a perspective view of the manually controlled actuator for the ejector or plunger.

Figure 6 is a perspective view of the ejector or plunger.

In the form of construction selected for illustration in the present application, the numeral 1 designates a horizontally elongated casing having a vertical portion 2 divided by partitions 3 into a plurality of magazines 4 for cigarettes or other articles of merchandise to be dispensed. The upper end of the magazine portion 2 is provided with a normally locked closure 5 so that the cigarettes or the like 6 may be inserted when said closure is opened. Weights, one of which is indicated at 7 in Fig. 2, are

placed upon the stacks of merchandise to feed them downwardly.

Within the base portion 1 of the casing, an inclined discharge chute 8 is provided, 60 said chute having an appropriate check 9 at its lower end. The space 10 above this chute constitutes a coin receptacle and a normally locked door 11 is provided for such receptacle. In the present showing, 65 the magazines extend downwardly through the top of the casing portion 1 and each magazine is preferably provided with a bottom 12 slightly above the chute 8, with an opening 13 in its front side and with an 70 opening 14 in its rear side. The ejectors pass through the openings 13 to project the articles of merchandise through the openings 14. One of the ejecting units is illustrated in detail in Figs. 2 and 3, and two of them 75 are disclosed in Fig. 4, it being understood however that one of such units is provided for each magazine, and as all of the units are duplicates, only one will be described.

The ejector proper is indicated at 15, 80 said ejector being shown in the form of a rod or plunger whose front end is received in the opening 13. This end of the plunger is provided with a narrow, wire-like horizontal terminal 16 upon which the lowermost of the articles 4, normally rests, said terminal engaging the central portion of the article as indicated by the dotted lines in Fig. 4. The rear end of the terminal 16 carries a vertical plate 17 which normally 85 closes the opening 14 as shown in Fig. 2. When the plunger 15 is forced rearwardly however, (see Fig. 3) it bodily projects the terminal 16 and one of the articles 6, through the opening 14. Then, the article 90 95 is free to tilt and drop from the terminal 16, into the chute 8 down which it slides to the purchaser.

A tubular actuator 18 slidably surrounds the front portion of the plunger 15, and a 100 transverse pin 19 passes through the actuator and through a longitudinal slot 20 in the plunger. The ends of the pin 19 project from the actuator and are engaged by one end of a coiled compression spring 21 which 105 surrounds said actuator, the other end of said spring being disposed against an appropriate guide 22 which is secured to the upper portion of the casing 1 for the actuator. In front of the spring, the actuator 110 115 18 is provided with an upstanding knob 23 passing through a slot 24 in the casing, and

in rear of the guide 22, the actuator is formed with a coin slot 24 normally registering with another slot 25 in the casing and with a third slot 26 in the plunger 15. Under the slots, a coin shelf 27 is provided.

Obviously, the actuator 18 is operated by the knob 23, against the action of the spring 21, when a coin is inserted through the slots, as shown in Fig. 2, and rearward forcing of said actuator which is then connected by the coin with the plunger 15, will rearwardly move the latter to eject one of the articles 6. As soon as the knob is released, the spring returns the actuator 18 and the plunger 15 to their normal positions, the coin in the meantime having been ejected from the slots 24 and 26.

In the preferred form of construction, a leaf spring 30 is stationarily anchored at one end within the casing and yieldably bears at its other end against the lower side of the plunger 15. When this plunger is moved to the position of Fig. 3, the spring 30 yields upwardly into the slot 26 and removes the coin therefrom, as fully shown in Fig. 3, after which the spring 19 returns the parts to normal.

To prevent any possibility of the plunger 15 being moved if the actuator 18 is idly moved, without insertion of a coin, I provide at least one, but preferably two spring detents 31 which are stationarily anchored in the casing and in the present showing are shaped to snap over rounded projections 32 on the plunger 15. When a coin is inserted and the plunger is moved, the detents 31 of course disengage the projections and when the plunger returns to its normal position, said detents re-engage said projections.

It will be seen from the foregoing that a rather simple and inexpensive, yet an efficient and desirable vending machine has

been provided, which may be used for numerous purposes. As excellent results are obtainable from the general structure disclosed, such structure may well be followed, but within the scope of the invention as claimed, numerous modifications may be made. Also attention may be here directed to the fact that the machine may be manufactured with any desired number of magazines for merchandise, and coin-controlled ejectors for such magazines.

I claim:—

1. A vending machine comprising a magazine for articles of merchandise, an ejector having a straight wire-like terminal extending in the direction of movement of said ejector and normally disposed under the magazine to engage the central portion of the lowermost article, said ejector also having a thrust shoulder to engage the article, and means for operating said ejector to project said wire-like terminal and the article beyond the magazine, permitting such article to tilt and fall from said terminal.

2. A vending machine comprising a vertical magazine for articles of merchandise, said magazine having openings in its front and rear sides at the lower ends thereof, a plunger passing rearwardly through the front opening of the magazine to engage the front end of the lowermost article for forcing it rearwardly through the rear opening of the magazine, said plunger having a rearwardly projecting wire-like terminal upon which the central portion of the lowermost article normally rests, and a plate carried by the rear end of said wire-like terminal to normally close said rear opening of the magazine.

In testimony whereof I have hereunto affixed my signature.

WALTER LOYD LINTON.
